UNITED STATES PATENT OFFICE.

WILLIAM JOHN BROOKS, OF LETCHWORTH, ENGLAND.

CALENDAR.

Application filed July 5, 1927, Serial No. 203,591, and in Great Britain January 8, 1927.

- This invention relates to calendars and like display devices in which it is desired to indicate or emphasize any one of a series of days or dates or other items of information; the series of dates, as for instance the days of the month, or other items being exposed to view and a particular date or item being singled out for notice by an adjustable indicator.
- 10 The object of this invention is to provide a calendar having means whereby any one of the days or dates may be conveniently displayed or indicated in a more prominent manner than the others and so that the means for doing this may be moved so as to be applied to any selected date. The indicator or means by which a selected date is emphasized is arranged to be easily movable while at the same time its method of support is not readily discernable. Further objects of the invention will be ascertained by the following description.
- Briefly the invention may be said to consist in employing a supporting frame of suitable construction having an opening in one wall for the exposure of calendar or other cards or plates. Means are provided for detachably supporting one or a number of interchangeable cards or plates behind the opening. A transparent disc or plate is arranged across the opening and in front of the calendar card which will show through it. The transparent disc or plate is provided with a ring or other conspicuous marking means and is held by friction so that it may be freely moved in any direction to permit the distinguishing mark to be aligned with any one of the dates on the exposed calendar card.
- 40 A suitable construction of frame may comprise front and rear wall members secured together or adapted to be secured together at their edges. The rear wall may be provided with slots or other means for supporting a number of calendar cards so that they may be readily changed, whilst the front member is provided with an opening through which one of the calendar cards may be viewed. The celluloid or other transparent disc or plate having a ring or other distinguishing mark thereon is arranged across the opening and between the front wall member and the calendar card which shows through it. Another method 50 of supporting the cards or plates may consist in providing an opening in the rear wall opposite to and larger than the opening in the front wall, such opening in the rear wall accommodating a relatively movable portion carrying a support for a number 60 of interchangeable cards.
- In the accompanying sheet of drawings two embodiments of the invention are illustrated.
- Fig. 1 being a front elevation of one form. 65
- Fig. 2 is a sectional elevation on the line 2-2 of Fig. 1.
- Fig. 3 is a sectional plan view on the line 3-3 of Fig. 1, and
- Fig. 4 showing the other form in sectional 70 plan.
- Referring to the drawings, the device illustrated is a calendar, and consists of a shallow rectilinear casing composed of a front wall 1, a rear wall 2 and an L section 75 periphery 3 uniting the two walls in spaced parallel relationship, the periphery being composed of thin metal or other suitable rigid material glued or otherwise secured to the two walls, or the edge of the front wall 80 may be bent over and secured to the back wall. The front wall has an opening 4 through which one of a number of cards or plates 5 is exposed, each card or plate 5 bearing suitable inscriptions, for instance 85 dates of the month.
- The cards or plates 5, which are preferably somewhat flexible, can be supported in a pair of parallel slots 6 in the rear wall 2. These slots 6 (Figs. 2 and 3) are wider 90 apart than the opening 4 and are each sufficiently wide to permit the easy entrance of the cards while imposing a slight bend on the cards at 5^a, the bend being exaggerated in the drawings for the sake of clearness. 95 The ends 5^b of the cards protrude from the slots sufficiently to permit easy withdrawal.
- The cards or plates are of a resilient nature so that they can be introduced into the two slots 6 by passing one end through a 100 slot, pressing the card or plate into the interior of the casing until the same end projects through the other slot 6, each slot having an enlarged thumb portion 7 to enable an operator to more readily effect this operation.
- The dimensions of the cards or plates 5 are such that each can lie flush against the front wall 1 of the casing and cover the opening 4. To enable a particular day 110 to be marked on the exposed card or plate a disc 8 of transparent material, for instance

celluloid is provided in the casing so as to be interposed between the front card 5 and the front wall 1 of the casing, being held in position friction-tight by reason of the slight pressure between front and rear walls. This disc has an opening 8^a, which may be a raised shallow cylinder as shown, or a ring may be fixed or formed on the surface of the transparent disc and may be of a distinguishing colour. By engaging the opening 8^a the disc 8 can be moved any direction to enable the opening or ring 8^a to be located over any particular date, as shown in Fig. 1.

An alternative method of supporting the cards, may consist in fitting into an opening in the rear wall a corresponding door or flap 9 hinged at 10 so that it can be swung away from the back 2 to expose a sheath 11 secured to the flap 9 and open at the front 20 to display through the opening 4 in the front wall 1, the front card of a number of cards 12 accommodated in the sheath 11. By opening the flap 9 a change of the card to be exposed can be effected.

25 I claim:—

1. A calendar and like display device, comprising a shallow casing, an opening in the front wall of the casing for exposing a card introduced in a pair of slots in the rear wall of the casing, the card having a greater length than the distance between the said slots and having ends projecting through both said slots, and a movable transparent disc having a distinguishing mark thereon.

35 2. A calendar and like display device, comprising a shallow casing, an opening in the front wall of the casing for exposing a card introduced in a pair of slots in the rear wall of the casing, the card having a greater length than the distance between the said slots, and having ends projecting through both said slots, and a transparent member movable in the casing and interposed between the front of the card and the front wall of the casing, such transparent member having a distinguishing part for locating over a selected part of the card being exposed.

50 3. A calendar and like display device, comprising a shallow casing composed of a front and rear wall connected in spaced relationship by bending the edges of one wall over and securing to the other wall, an opening in the front wall, a pair of parallel spaced slots in the rear wall, a number of cards for introduction through both slots so that one of the cards is exposed through said opening and a movable transparent member interposed between the exposed cal-

endar card and the front wall and a distinguishing mark on the transparent member.

4. A calendar and like display device, comprising a shallow casing composed of a front and rear wall connected in spaced relationship by a surrounding uniting strip, an opening in the front wall, a pair of parallel spaced slots in the rear wall, a number of cards for introduction through both slots so that one of the cards is exposed through said opening, and a transparent member movable in the casing and interposed between the front of the card and the front wall of the casing, such transparent member having a distinguishing part for locating over a selected part of the card being exposed.

5. A calendar and like display device comprising a shallow casing having a front wall with an opening for the exposure of a card bearing matter to be displayed and a rear wall between which and the front wall the card is adapted to be accommodated, and a transparent plate of a greater area than the said opening for covering substantially the whole of the exposed area of the displayed card, said transparent plate being frictionally held between the front of the said displayed card and the front wall of the casing solely by the pressure exerted upon it due to the compression between front and rear walls, and being capable of such movement within the casing, in any direction in its own plane, that a fixed distinguishing mark upon it can be aligned with any portion of the displayed matter on the card.

6. A calendar and like display device comprising a shallow casing having a front wall with a centrally located opening for the exposure of a card bearing matter to be displayed and a rear wall between which and the front wall the card is adapted to be accommodated, a transparent disc of a greater area than the said opening for covering substantially the whole of the exposed area of the displayed card, said transparent disc being frictionally held between the front of the said displayed card and the front wall of the casing solely by the pressure exerted upon it due to the compression between front and rear walls, and being capable of such movement within the casing, in any direction in its own plane, that a fixed central distinguishing mark upon it can be aligned with any portion of the displayed matter on the card, and accommodation within the casing for the disc around the entire periphery of the front wall opening.

WILLIAM JOHN BROOKS.
